DRAWER PULL

Orville B. Solie, Rockford, Ill., assignor to Kroehler Mfg.
Co., a corporation of Delaware

Filed Oct. 17, 1968, Ser. No. 14,033

Term of patent 14 years

Int. Cl. D8—03
U.S. Cl. D8—158

FIG. 1

FIG. 2

FIG. 3

FIG. 1 is a front elevational view of a drawer pull showing my new design;

FIG. 2 is an end elevational view thereof; and
FIG. 3 is a top plan view thereof.

The dominant features reside in the solid line portions.
I claim:

The ornamental design for a drawer pull, as shown and described.
